UNITED STATES PATENT OFFICE.

JOSEPH GUY, OF NEW YORK, N. Y.

HEATING ATTACHMENT FOR GAS COOKING-STOVES.

SPECIFICATION forming part of Letters Patent No. 530,640, dated December 11, 1894.

Application filed October 10, 1893. Serial No. 487,779. (No model.)

To all whom it may concern:

Be it known that I, JOSEPH GUY, a citizen of the United States, residing at New York, in the county of New York, State of New York, have invented certain new and useful Improvements in Heating Attachments for Gas Cooking-Stoves; and I do declare the following to be a full, clear, and exact description of the invention, such as will enable others skilled in the art to which it appertains to make and use the same.

Where gas and oil stoves are employed for cooking it is often desirable in cool weather to obtain from them heat for the purpose of warming the apartment in which such stoves are located, or adjoining rooms. The burners of such stoves are, however, generally at the top of the device and not capable of imparting to the atmosphere of the room any great amount of heat.

It is the object of my improvement to provide a simple and inexpensive attachment for ordinary gas, gasoline or oil cooking stoves by the use of which a great amount of heat can be economically obtained therefrom, and which may be readily put in place or removed accordingly as it is desired to use the stove for heating or cooking.

With such object in view my invention consists in the parts and combinations thereof hereinafter set forth and claimed.

In order to make my invention more clearly understood I have shown in the accompanying drawings means for carrying it into practical effect without limiting my improvements, in their useful applications to the particular construction which, for the sake of illustration, I have delineated.

In said drawings:—Figure 1 is a perspective view of a heater embodying my invention. Fig. 2 is a vertical sectional view of the same. Fig. 3 is a horizontal sectional view on line 3—3 of Fig. 2.

Referring to the drawings, 1 indicates the burner or burners of an ordinary gas cooking stove, portions of the top of which latter are shown at 2.

3 indicates one or more ascending drums or ducts, their number depending on the number of burners to be utilized for heating purposes, 50 open at their lower ends and adapted to fit over said burners and act as flues therefor.

4, 4, are elbows formed at the upper ends of the drums 3 and extend horizontally to a central descending box or duct 5 with which 55 they communicate. The box is otherwise closed at its upper end. It extends, from the place where it receives said elbows or continuations of the drums 3, downward to a point somewhat above the level of the burners, and is provided with means for limiting the exit of the air therefrom, so as to cause the air and products of combustion, carried up the drums 3 from the burners, to thoroughly heat the drums and box 5 before they 65 escape. Such means may consist of a plate 6 which partially closes the end of the box 5. Preferably the air opening or openings, shown at 7, is or are arranged near the side walls or plates of the box 5 as shown so as to cause the 70 heating air to pass down close to said walls and highly heat the box on all sides.

8, 8 indicate doors in the drums 3 near their lower ends and in proximity to the burners 1. Through these doors the burners may be 75 lighted, and an additional quantity of air may be admitted to the drums; and, being provided with panes 9 of mica, serve to display the burner flames. At their lower ends the drums are shaped as by notches 10, to interlock with 80 portions of the stove top such as the bars 2^a and secure the heater from falling over.

I prefer to construct the attachment of sheet iron, surmounting it by an ornamental top or vase 11.

12 is a door formed in the side of the box 5 whereby the exit of a greater quantity of air may be permitted, and through which such air may be thrown horizontally outward into the room in a strong current.

When in place and in operation the drums 3 can be heated to cherry redness by the amount of gas ordinarily consumed by cooking burners, and the air from said drums com-

bining in the box 5 the latter is also very highly heated, the whole device serving to produce much warmth and obtaining the maximum calorific effect from the gas consumed.

5 What I claim is—

A detachable heater for gas, or oil or other cooking stoves, consisting of supporting drums open at their lower ends and adapted to rest upon the stove over the burners thereof, and 10 the central depending box or drum carried

by and communicating with said supporting drums, and having at its lower end an exit opening or openings for the heated air, substantially as set forth.

In testimony whereof I affix my signature in 15 the presence of two witnesses.

JOSEPH GUY.
